CUFF LINK

Clement S. Marien, Attleboro, Mass., assignor to Swank, Inc., a corporation of Delaware

Application January 7, 1955, Serial No. 430,457

2 Claims. (Cl. 24—102)

This invention relates to a cuff link of the type more particularly designed for use in a shirt having so-called French cuffs in which the cuff is folded back upon itself and button holes are provided in both folded-back portions for the reception of a cuff link.

In the use of cuff links for the type of cuff in which there are button holes in each marginal edge portion, sometimes cuff links comprising two members which are completely separable are utilized so that the cuff may be opened for more easily removing the shirt. In other cases where the heads which engage the opposite edges of the cuff are in fixed relation, one of the heads must be removed from the button hole in order that the cuff may be opened for easily removing the shirt.

One of the objects of this invention is to provide a cuff link which will have its opposite members with heads so connected that there may be an enlargement of the distance between them so that the shirt may be easily removed over the wrist without completely separating the members having the heads which engage the buttons of the cuff.

Another object of the invention is to provide an enlargement of the connection between the heads of a cuff link without some elastic action. Another object of the invention is to provide an extendable connection between the heads of a cuff link which will maintain these heads in a desired relative position one to the other.

Another object of this invention is to provide a relatively rigid link when in collapsed position with no flexibility afforded.

With these and other objects in view, the invention consists of certain novel features of construction as will be more fully described and particularly pointed out in the appended claims.

In the accompanying drawings:

Figure 1 is a side elevation of a cuff link constructed in accordance with this invention;

Figure 2 is a view similar to Figure 1 but showing the cuff link in expanded position;

Figure 3 is an exploded view with parts in section of the different rigid parts which go to make up the link;

Figure 4 is a sectional view on line 4—4 of Figure 1, but on a larger scale, showing the clasping action between certain of the parts.

In proceeding with this invention, I provide a pair of members, each of which will have an ornamental head to engage the outer surface of the cuff and a post which will extend through the button holes of the cuff. These posts are then each provided with arms which extend laterally in opposite directions, and the outer free ends of the post are then connected by a rigid link which will nest into the arms when the button is in collapsed position and be held in this position by recesses in one part and protuberances in the other to enter the recesses. The posts are beveled at their inner ends so that they will engage and be in substantial alignment when the button is in collapsed position.

With reference to the drawings, the cuff link comprises a pair of members 10 and 11 which are substantially duplicates in construction. Each of these members comprises a head 12 which will be ornamental and which is designed to engage the outer surface of the shirt cuff. A

2

post 13 projects from the head at right angles thereto and may in some cases be of the same piece of material and integral with the head, or the post may be soldered to the head. At the inner end of the post there extends laterally from the post and at right angles thereto an arm 14 which will be of channel shape in cross section having opposite side walls 15 and a bridging connecting wall 16. The end of the post is beveled as at 17 so that the two posts 13 may be in alignment with the bevel 17 at 45°, forming a joint between them. The members 10 and 11 will be positioned in opposed relation so that the arm 14 of one extends in a diametrically opposite direction from the arm 14 of the other, and as they are in opposed relation, the beveled ends 17 will mate as shown in Figure 1. The free ends 18 of each of the arms are connected together by a rectangular link 19 which has openings in its ends as at 20 so as to register with openings 21 in the ends of the arms 18 and a pivot pin 22 will pass through these registering openings so as to pivotally connect the link 19 with the free ends 18 of the arms 14.

This link 19 is of rectangular construction as will be seen in Figure 4 and closely fits between the walls 15 in such a manner as to bottom upon the wall 16 of this channel arm 14. Thus, the members 10 and 11 may be removed from the position shown in Figure 1 to the position shown in Figure 2 by reason of the link 19 swinging on its pivots 22, and by reason of the close fit of the link in the channel the parts 10 and 11 may be moved to closed position and be guided into correct alignment by the rectangular link and channel guiding the parts to contracted position.

The parts may be held in this contracted position by recesses 23 in the link and protuberances 24 struck in the side walls of the channel which may leave depressions 25 in the outer surface so that as the link is moved to contracted position, the resilient walls 15 will be slightly spread apart and the link seated in the channel and held therein by reason of the protuberance springing back into the recesses 23 by the inherent resiliency of the stock so as to hold the cuff link in closed position.

By reason of the rectangular fitting of the movable parts and the construction above described, a rather rigid cuff link is provided when in this folded position. It will be readily apparent that the heads 12 will engage the outer surface of the cuff about the button hole openings while the arms 14 will be between the inner surface of the cuffs. The link 19 may be made of such extent as to afford a separation of the opposite parts of the cuff as may be desired.

I claim:

1. A cuff link comprising a pair of members, each having a head, a post at substantially right angles to the head, and an arm extending laterally from the post terminating in a free end with the free ends of the arms in opposed relation, each of said arms being channel shaped in cross section and made of the same material as the said posts and integral therewith, a link connecting the free ends of said arms and of a size to nest into the channel of the arms, the ends of said posts distant from the head being beveled and in overlapping relation when the members are in contracted position, and means for detachably holding said link in nested relation within said arms.

2. A cuff link according to claim 1 wherein the ends of said posts are beveled at an angle of 45°.
